Inventor:
Harry B. Stein

By J. Daniel Stuve
Attorney

UNITED STATES PATENT OFFICE.

HARRY B. STEIN, OF CHICAGO, ILLINOIS.

WINDOW CONSTRUCTION.

Application filed October 19, 1926. Serial No. 142,584.

My invention relates to window construction; and the main object of the invention is to provide such a construction which includes housing means arranged or built in the wall 5 of a building and forming part of the window frame, and window sash means which is 10 slidable through said frame part into said housing means to be concealed therein and to entirely clear the window opening for admission of air therethrough. Another object 15 is to provide curved spring strips or members on the sash and frame and housing means to form an air tight fit. And a further object is to provide track means on the 20 sash and frame and housing means, and curved spring means on said track means to provide a slidable air tight fit.

Other objects and advantages are attained 25 with my invention, as will become apparent from the following description taken in connection with the accompanying drawings, forming part of this specification, and in which,

Fig. 1 is a elevational view of a window 30 construction embodying my invention;

Figs. 2 and 3 are vertical sectional views on lines 2—2 and 3—3 of Fig. 1;

Fig. 4 is an enlarged horizontal sectional view on line 4—4 of Fig. 1;

Fig. 5 is a horizontal sectional view on line 35 5—5 of Fig. 1;

Fig. 6 is a vertical sectional view on line 6—6 of Fig. 1;

Fig. 7 is an enlarged vertical sectional view on line 7—7 of Fig. 1;

Fig. 8 is an enlarged vertical sectional view on line 8—8 of Fig. 1; and

Fig. 9 is a vertical cross sectional view on line 9—9 of Fig. 8.

In the drawings I have illustrated the preferred form of my invention which comprises housing means 12 arranged and placed in the wall 13 of a building, along the sides of the window, and forming a part of the window frame and being connected to the side jamb 14 thereof, an opening or slot 15 being provided on the side for the reception of the window sash 16 into the housing. This housing is constructed in a manner and size to suit the sash and the building on which used, and preferably includes side members 17 with connecting panels 18 therebetween, and an end member 19 with a stop element or buffer 20 thereon engaged by the sash. A suitable corner piece or member 21 is placed over side member 17 at the inward corner of

the housing, and a suitable sash strip 22 is placed over member 21 and fastened with a few screws 23 on said corner member 17 of the housing, to engage at the inward side of 60 the sash. This strip may thus be readily taken off to permit convenient removal of the sash, from the window.

The sash is provided in any desired style or design, single or double, and its side 65 member 16' is arranged to fit closely but slidably in the slot 15 of the housing. A reinforcing plate 24 is fastened to the side edge of said member 16', and preferably has a rib 24' set tightly in a groove in member 70 16', thus forming an air tight fit; and furthermore a curved resilient member 25, preferably a strip of spring bronze, is fastened to said plate and slides therewith in the housing, being arranged to closely engage the 75 window frame and form an air tight fit therewith. With the use of two sashes in the window, one is provided at the meeting edge with a channel member 26, and the other with a rib 27 closely fitting therein; and an 80 overlapping flange 28 on one sash fits snugly in a corner groove in the other sash, while a closing strip 29 covers the outer joining edges of the two sashes, thus providing a positive 85 air tight and storm tight fit.

I provide improved track means, preferably at the top and bottom of each sash and on the window frame and housing, to provide guide means and a support for easily sliding the sash. This track means preferably includes a plate 30 fastened under the top member of the housing and under the top member of the window frame, said plate having a rail or rib 31 thereon which is embraced by a companion channel member 32 90 mounted on the top of the sash. Curved resilient members 33, preferably strips of spring bronze, are placed between members 31 and 32, as by being fastened on the rail, and closely but slidably engaging the channel member, so as to form an air tight fit. The lower track means preferably includes a rail 34 fastened on the window stool 35 and on the bottom member of the housing, and also a channel member 36 which is set into the bottom edge of the sash; furthermore a pair of casings 37 are set into said bottom of the sash and contain a shaft 38 with an inner wheel 39 mounted thereon and forming a large axle for an outer wheel 40 rotating thereon with the use of antifriction bearings 41 and traveling along rail 34. Side flanges

42 on said casing extend along the sides of the rail; and curved resilient members 43, preferably of spring bronze, are mounted on the rail and slidably engage the channel member to form an air tight fit, between the sash and the window stool.

It is apparent from the above disclosure that I have provided a construction where in the window is moved out of the window 10 opening so as to entirely clear said opening for the entrance of fresh air, and also that the window sash is entirely concealed and protected in the housing and out of the way, being thus a vast improvement over 15 the usual casement windows or swingable windows, and also over the usual slidable sashes which slide upon one another thus clearing only one-half of the window opening; and it is also apparent that an air 20 tight and storm tight fit is formed with this construction, and especially with the curved spring strips used at the connections of the various members.

What I claim as my invention and desire 25 to secure by Letters Patent is:

1. A window construction comprising housing means consisting of frame members and connecting panels therebetween placeable in the wall and forming part of 30 the window frame, there being a slot in said frame part, and track means with spring strips for sliding the window sash through said slot into said housing means.

2. A window construction comprising a 35 slidable window sash, and rotary anti-friction means including concentric rollers built and concealed in said sash for readily moving and for supporting said sash.

3. A window construction comprising a 40 housing forming a side part of the window frame, a sash movable sideways through said frame into said housing, and track means on said sash and said frame and said housing including rail means mortised 45 weather-tight in the frame for readily sliding said sash into said housing.

4. A window construction comprising a 50 frame, sash means movable sideways in said frame, track means including channel means on top and bottom of said sash means, and rail means with curved springs

mounted weather-tight on said frame engageable in said channel means for slidably guiding and supporting said sash means.

5. A window construction comprising a 55 frame, sash means slidable in said frame, track means including channel means and rail means on said sash means and said frame for sliding said sash means, and spring strips between said channel means 60 and said rail means to provide an air tight slidable fit.

6. A window construction comprising a frame, a housing forming a side part of said frame, sash means slidable into said 65 housing, track means on said sash means and said frame and said housing, including channel means and rail means, and spring means between said channel means and said rail means to form an air tight slidable fit 70 therebetween.

7. A window construction comprising housing means built in the wall and forming part of the frame, sash means slidable into said housing means, and a curved 75 spring strip on the side of said sash means, inside said housing, to engage said frame part and form an air tight fit therewith.

8. A window construction comprising a frame, a housing forming a part of said 80 frame, sash means slidable into said housing, track means on said sash means and on said frame and housing, including channel means and rail means with curved spring means therebetween to form a slidably tight 85 fit, and curved spring means on the side of the sash means within the housing, for engaging the frame and form a tight fit.

9. A window construction comprising a frame and a housing connected thereto, a 90 sash member slidable into said housing, track means including a rail on said frame and housing, curved spring means on said rail, channel means set in said sash and fitting closely over said spring means, and 95 casing means including rotary means set in the sash with said channel means, for supporting the sash on said rail, and to travel freely thereon.

In testimony whereof I have signed my 100 name to this specification.

HARRY B. STEIN.
